UNITED STATES PATENT OFFICE.

JAMES T. FIELDS AND DANIEL E. RYAN, OF MASON CITY, ILLINOIS.

RAIL DRIVER.

Application filed April 5, 1922. Serial No. 549,725.

To all whom it may concern:

Be it known that we, JAMES T. FIELDS and DANIEL E. RYAN, citizens of the United States, residing at Mason City, in the county 5 of Mason and State of Illinois, have invented certain new and useful Improvements in Rail Drivers, of which the following is a specification, reference being had to the accompanying drawings.

10 This invention relates to improvements in rail drivers, and more particularly to an improved device for driving a rail longitudinally to return the same to its proper position after creepage thereof.

15 An important object of the invention is to provide a device of this type wherein not only is the movement of the driver, which is usually in the form of a length of rail, maintained in position and in alignment 20 with the rail to be driven but is likewise so supported that it may be readily moved to bring it into engagement with the rail to be driven.

25 A still further object of the invention is to provide a device of this character which is simple in construction and arrangement, readily applied to position, durable in service and a general improvement in the art.

30 These and other objects we attain by the construction and arrangement shown in the accompanying drawings wherein for the purpose of illustration is shown a preferred embodiment of our invention and wherein 35 like reference characters designate like parts throughout.

In the drawings:

Figure 1 is a side elevation of a rail driver constructed in accordance with our invention; and

Figure 2 is a section on the line 2—2 of Figure 1.

Referring now more particularly to the drawings, the numeral 10 indicates a member adapted to straddle a rail R' of the track next adjacent the rail R to be driven. In the present embodiment of the invention this is shown as comprising an inverted U-shaped member having the eight portion 11 arms 45 ranged upwardly and the arms 12 thereof arranged upon opposite sides of the rail R'. Headed gudgeons 13 extend through the arms 12 and are provided at their inner ends with rollers 14 of such size that they project 50 above the upper surface of the rail R' when the device is in applied position, the rollers 55

14 being spaced apart a sufficient distance to permit their placement over the rail R' with the rail therebetween. These rollers support a driver 15 preferably in the form 60 of a length of rail and the upper ends of the arms are provided with inwardly extended portions 16 restricting the space therebetween so as to prevent tipping or tilting of the driver 15.

65 The lower ends of the arms 12 are preferably provided with ears 17 through which extend securing elements attaching to the lower ends of the arms plates 18 adapted to rest upon the ties T of the track upon opposite sides of the rail R'. When in this position the head of the rail R' is engaged at its side faces by lugs 19 extending inwardly from the sides of the arms 12 of the U-shaped member which prevent tipping or 70 shifting of the member 10 with relation to the rail. As is well known to those familiar with the art, when it is desired to drive the rail R the same is loosened and the end upon which the driving is to be done is elevated 75 80 and held in such elevated position by a suitable brace B.

85 In employing our device the members 10 are placed upon the rail R' with the plates 18 thereof engaging the ties at opposite sides 90 of the rail and when in this position the rollers 14 have their outer edges projecting above the upper surface of the rail R', as hereinbefore stated. Upon these rollers the edges of the base of the driver rail 15 are 95 rested, two of the members 10 being provided, arranged adjacent opposite ends of the driver rail 15. The engagement of the lugs 19 against the side faces of the rail R' 100 effectually prevents shifting movement of the members 10, permitting the reciprocation of the rail driver 15 within the guides afforded by the arm 12 of the U to drive the rail R longitudinally to the desired position.

105 From the foregoing it is believed to be obvious that a rail driver constructed in accordance with our invention is particularly well adapted for the purpose for which it is intended by reason of the fact that it not only provides an anti-friction support for a driver rail but guides and prevents tipping thereof. It will furthermore be obvious that the construction as hereinbefore set forth is capable of some change and 110 modification without materially departing from the spirit of our invention and we ac-

cordingly do not limit ourselves to such specific structure except as hereinafter claimed.

We claim:

1. In a rail driver, a member adapted to straddle a rail having portions engaging the ties upon opposite sides of the rail and other portions engaging opposite side faces of the rail head, and means carried by the member for roller supporting and for guiding the driver.
2. In a rail driver, an inverted U-shaped member adapted to straddle a rail and provided at the lower ends of the arms thereof with tie engaging portions, rollers rotatably mounted upon the inner surface of the arms of the U and having the upper ends thereof projecting above the upper surface of the rail, and a driver embodying a base having its edge portions resting upon said rollers.
3. In a rail driver, an inverted U-shaped member adapted to receive between the arms thereof a rail, tie engaging portions carried by the lower ends of the arm portions, headed gudgeons extended through each of the arms and each provided at their inner ends with rollers, the upper ends of said rollers projecting above the upper edge of the rail, and a driver member having a base, the edges of which rest upon said rollers.
4. In a rail driver, an inverted U-shaped member adapted to receive between the

arms thereof a rail, tie engaging portions carried by the lower ends of the arm portions, headed gudgeons extended through each of the arms and each provided at their inner ends with rollers, the upper ends of said rollers projecting above the upper edge of the rail, a driver member comprising a rail having the edges of the base thereof resting upon said rollers, and projections carried by the upper ends of the arms and intermediate which the head of the driver member operates.

5. In a rail driver, an inverted U-shaped member adapted to receive between the arms thereof a rail, tie engaging portions carried by the lower ends of the arm portions, headed gudgeons extended through each of the arms and each provided at their inner ends with rollers, the upper ends of said rollers projecting above the upper edge of the rail, a driver member comprising a rail having the edges of the base thereof resting upon said rollers, projections carried by the upper ends of the arms and intermediate which the head of the driver member operates, and lugs secured to said arms and engaging opposite faces of the rail whereby to prevent tipping or angular deviation of the U-shaped member.

In testimony whereof we hereunto affix our signatures.

JAMES T. FIELDS.
DANIEL E. RYAN.
